Inventor.

UNITED STATES PATENT OFFICE.

FRANCIS V. M. HUDSON, OF BROOKLYN, NEW YORK.

WALL OF BUILDING-BLOCKS.

No. 867,043.

Specification of Letters Patent.

Patented Sept. 24, 1907.

Application filed February 8, 1906. Serial No. 300,056.

To all whom it may concern:

Be it known that I, FRANCIS V. M. HUDSON, a citizen of the United States, residing at 171 Linden avenue, Brooklyn, county of Kings, and State of New York, 5 have invented certain new and useful Improvements in Walls of Building-Blocks, fully described and represented in the following specification and the accompanying drawings, forming a part of the same.

The present invention provides means to utilize U- 10 shaped blocks in a novel manner in the building of walls to form continuous vertical air spaces or flues, and to secure the effective bonding not only of different courses, but of adjacent rows of blocks in the same course.

15 The term "U-block" is, for convenience, applied herein to a block formed of a tie-bar with end-projections or legs at right angles to the same; the length of such legs, in relation to the tie-bar, being varied to any extent that is desirable, in the construction. The tie-bars and legs form flanges of uniform depth which are set vertically in the courses.

The fundamental feature of the invention is the arrangement of the U-blocks in rows with their alternate ends opposed so as to form a continuous zigzag design 25 resembling a so-called Grecian border, with continuous vertical air spaces or flues within the wall. A wall may be formed of the blocks thus arranged in a single row, or a double or triple row, and the junction of the rows at the corner of a wall requires some special 30 filling-pieces, as hereinafter described. Such disposition of the blocks leaves interspaces between the ends of the blocks at both sides of the wall, and these gaps are closed by "filling-blocks" which are preferably made of T-shape with a central web extended 35 across the row nearly to the tie-bar of the opposed U-block. Such central web upon the T-block not only forms a bond between the opposed sides of the row, but supports the end legs of the U-blocks in a superposed course.

40 The vertical flanges of the blocks in the several courses are overlapped upon one another so as to break joints between the courses, and in the corner of a wall such overlapping leaves a space one-half the breadth of a block, which may be conveniently filled by an angle-piece, made with vertical flanges to form air spaces or other shapes.

45 Slight differences in the shape of the U-blocks may be made without departing from the invention, and such modifications are illustrated in the annexed drawing, in which

Figure 1 illustrates the zigzag arrangement of the U-blocks; Fig. 2 illustrates the filling of the gaps in opposite sides of the row by T-blocks, and shows a corner of one course; Fig. 3 shows a modification of the U-blocks in which the legs on the same block are of different lengths; Fig. 4 shows a modification of the U-

blocks with a tongue at the center of the tie-bar opposed to the web on the T-block; Figs. 5 and 6 show methods of indenting the outer corners of the U-blocks to equalize the exposed surfaces of the tie-bars and T-blocks; Fig. 7 shows U-blocks with lugs at the ends to form a greater contrast with the breadth of the heads upon the T-blocks; Fig. 8 is a perspective view of one of the U-blocks shown in Fig. 1; Figs. 9 and 10 are plans of two-contiguous courses in a two-row wall, showing 65 the disposition of the blocks to break joints in the courses; and Fig. 11 is a cross section on line 11—11 in Fig. 7, showing an angular joint between the legs of the opposed U-blocks, and a bond inserted in such joint.

In Fig. 1, *a* designates the tie-bar of each U-block, and *b* the legs, the alternate ends or legs of the block being opposed in the rows; that is, the right-hand leg of each block is opposed to the left-hand leg of the block on the opposite side of the row. Such arrangement when viewed in plan shows the zigzag design, in 75 which spaces or gaps *c* are produced between the ends of the U-blocks. Fig. 2 shows these gaps upon the face of the row filled by the heads *d* of T-blocks having each the web *e* extended across the middle of the gap nearly to the tie-bar of the opposed U-block. The heads, 80 T-bars, webs and legs are all disposed vertically in the wall so that their interspaces form vertical air flues or passages for the circulation of air. An angle or L-shaped piece *f* is shown at the end of the row, which in one course is adapted to support the end or corner of the U- 85 block in a superposed course. The arrangement of the blocks in such superposed course is shown in Fig. 4, the corner in such case being formed by the U-block itself, but a space occurring on one side of the corner, which requires an L or angle-block *g* to fill it, in order 90 to connect with the U-block of the adjacent row.

The disposition of the blocks in the two courses shown in Figs. 2 and 4, bring the joints of the U-blocks in one course over the webs of the T-blocks in the course below, and all parts of the blocks are therefore 95 supported in the several courses, leaving continuous vertical air-spaces *i*, shown in the several figures.

In Fig. 3, the legs *b'* of the U-blocks are shown of unequal length, which prevents a line of joints along the middle of the row, which would weaken the wall-structure under strain. The tie-bars *a* of the U-blocks are shown in Fig. 4 formed with tongues *h* projected toward the webs of the T-blocks, which are correspondingly shortened.

With the alternate ends of the U-blocks opposed, the 105 spaces or gaps *c* are necessarily less than the length of the tie-bars *a* of the blocks, and to equalize the width of the heads of the T-blocks, and the tie-bars of the U-blocks, the corners of the U-blocks may be notched with a rectangular recess, as shown in Fig. 5, or with a bevel, as shown in Fig. 6, thus making all the vertical joints upon the wall at the same distance apart.

To form a different aspect of the joints upon the wall, lugs *l* may be projected from the corners of the **U**-blocks (that is, the ends of the tie-bars *a*) as shown in Fig. 7, thus contracting the gaps and making the heads 5 *d'* of the **T**-blocks only one-half as wide as the exposed surface of the tie-bar.

Figs. 9 and 10 show a wall made of two rows of the opposed **U**-blocks, the gaps between the blocks being set in line with one another in each course, and the 10 space in such gaps within the wall provided with filling-blocks having webs *e'* which are adapted to support the legs *b* of the **U**-blocks in the superposed course.

Figs. 9 and 10 show two contiguous courses adapted 15 one to set over the other; the **U**-blocks themselves forming the corner in Fig. 9, and the **U**-blocks in Fig. 10 falling short of the corner, as in Fig. 2, and the corner filled out by a special block *k* and **T**-piece *m*. Other blocks *k'* and *k''* are employed to bond the joints together in the contiguous courses at the corner.

20 In practice, the webs upon the **T**-blocks and the ends of the legs upon the **U**-blocks would not be set in contact with the opposed projections, but a space *p* would be left to prevent the passage of moisture through the wall, as shown in Fig. 5. In turning 25 corners, and in forming the inclosures for bay-windows, and in building other irregularities in house walls, the pieces necessary to preserve the contour may be cut from the **U**-blocks or **T**-pieces, and in special cases, other pieces may be provided, as shown in Figs. 3 and 30 4. The blocks used in building a double or triple wall may have the same modifications as those used in the single wall. I do not confine myself to walls of uniform thickness, but when necessary to construct chimney flues, buttresses, &c., may increase the length of 35 the projections upon the blocks, and thus extend the wall within or without the line. In some cases, it is necessary to use angle-pieces and other special forms in order to preserve the contour, but no claim is made to such special pieces.

40 It will be seen from the above description, that the combination of **U**-blocks and **T**-blocks is adapted to form overlapping joints in the most advantageous manner in contiguous courses, and to thus form a wall of great strength while preserving the continuity of the 45 vertical passages *i* which provide ventilation.

The legs *b* of the **U**-blocks may be beveled, as shown in Fig. 11, so as to break joints upon different lines at the top and bottom of each course, and a bond may also be extended across the joint of the legs, as shown at *j* 50 in Fig. 11, to tie the opposite blocks together.

Having thus set forth the nature of the invention what is claimed herein is:

1. In a wall, the combination in one course, of a series of **U**-blocks having their alternate ends opposed, and the 55 surface gaps filled with auxiliary blocks.

2. In a wall, the combination in one course, of a series of **U**-blocks having their alternate ends opposed and the surface gaps of the interspaces filled with the heads of **T**-

blocks, the web of each **T**-block extending across the center of the interspaces.

3. In a wall, the combination in one course, of a series of **U**-blocks having their alternate ends opposed, and each provided with a projection upon its inner side, and the surface gaps filled with the heads of **T**-blocks, and with their webs extended nearly across the centers of the gaps.

4. In a wall, the combination, with a course containing a series of **U**-blocks having their tie-bars upon the face of the wall and their alternate ends opposed and the end legs of the **U**-blocks of unequal length, of a superposed course having similar **U** blocks with their tie-bars upon the face of the wall and their legs arranged to break joints with the corresponding legs in the contiguous course, and filling blocks of **T**-shape having their heads inserted in the spaces between the tie-bars in the respective courses, and their webs extending nearly across the centers of the gaps between the legs.

5. In a wall, the combination in one course, of a series of **U**-blocks having their alternate ends opposed and the surface gaps filled with the heads of **T**-blocks, the web of each **T**-block extending toward the tie-bar of the opposed **U**-block, and the outer corners of the legs being indented and the heads of the **T**-blocks fitted thereto, to equalize the exposed surfaces of the tie-bars and heads.

6. In a wall, the combination, with a course, including a corner, containing a series of **U**-blocks having their alternate ends opposed and forming a zigzag design with surface gaps between the ends of the **U**-blocks, of a superposed course having similar **U**-blocks overlapped to break joints upon the course below, and **T**-blocks having their heads fitted to the surface gaps and their legs extended into the space between the ends of the **U**-blocks, and angle-blocks filling the space at the corner caused by such overlapping, substantially as set forth.

7. In a wall, the combination in one course, of a series of **U**-blocks having their alternate ends opposed, and the surface gaps filled with the heads of **T**-blocks, and the end legs of the **U**-blocks being beveled to break joints at different lines at the top and bottom of the course.

8. In a wall, the combination in one course, of a series of **U**-blocks having their alternate ends opposed, and the surface gaps filled with the heads of **T**-blocks, and the end legs of the **U**-blocks being beveled to break joints at different lines at the top and bottom of the course, and a bond extended across such beveled joint to tie the opposed blocks together.

9. In a wall, the combination in one course, of two rows of **U**-blocks having their extreme ends opposed, with the openings of the legs adjacent to one another within the wall, and filling blocks inserted in such openings.

10. In a wall, the combination in one course, of two rows of **U**-blocks having their extreme ends opposed, with the openings of the legs adjacent to one another within the wall, and filling blocks inserted in such openings, and having webs intermediate to the legs of the **U**-blocks, to support such legs in a continuous course.

11. In a wall, the combination, with one course including a corner, and two rows of **U**-blocks with their extreme ends opposed, and the openings of their legs adjacent to one another with filling blocks in such openings, of a superposed course with the blocks of the rows overlapped to break joints upon the course below, and filling blocks inserted in the space at the corner caused by such overlapping.

In testimony whereof I have hereunto set my hand in the presence of two subscribing witnesses.

FRANCIS V. M. HUDSON.
